UNITED STATES PATENT OFFICE.

ROBERT ABBOTT HADFIELD, OF WESTMINSTER, AND ALEXANDER GEORGE MCKENZIE JACK, OF SHEFFIELD, ENGLAND.

CAP FOR ARMOR-PIERCING PROJECTILES.

Application filed December 18, 1918. Serial No. 267,276.

To all whom it may concern:

Be it known that we, Sir ROBERT ABBOTT HADFIELD, baronet, F. R. S., and ALEXANDER GEORGE MCKENZIE JACK, subjects of the

King of Great Britain and Ireland, residing, respectively, at the city of Westminster, England, and Sheffield, in the county of York, England, have invented Improvements in or Relating to Caps for Armor-Piercing Projectiles, of which the following is a specification.

This invention has reference to the caps fitted to armor piercing projectiles with the object of enabling such projectile to successfully perforate hard faced armor plates.

Heretofore such a cap has been provided with a smooth conical, conoidal, rounded, that is to say convex, or concave front end portion, or with a centrally arranged rounded or flat end portion, projecting forwardly from the remaining portion of the cap, for attacking the plate and weakening it before the point of the projectile reaches it, so as to facilitate perforation of the plate by the projectile.

With all these constructions of cap, the smooth front end portion of the cap on impact against a hard faced plate, compresses the surface portion of the plate and forms a single indentation or depression therein, and, whilst weakening the plate to some extent, compresses the portion of the metal directly struck. Furthermore, there is a liability of the capped projectile when striking on an armor plate obliquely, especially at a large angle, slipping along the surface of the plate and failing to indent the plate in such a manner as to centre it and enable the cap and projectile to successfully attack the plate in such a manner as to enable the projectile to perforate the plate.

Now the present invention has for its object to enable the cap of a capped armor piercing projectile on impact against a hard faced armor plate, to engage, dig into and damage the plate, either when striking normally, or obliquely, and in the latter case, even at a large angle, in a better manner than heretofore and so as to shatter, break up or disintegrate the hard face of the plate

in a more effective manner than heretofore usual, in order the better to ensure perforation of the plate by the projectile in the desired manner.

For this purpose, the front end portion 55 of the cap instead of being made with a smooth surface as heretofore, is provided with a number of cutting or indenting points, blades, edges, ridges or equivalent, so as to form, in effect, a roughened, serrated, 60 ribbed or irregular surface adapted, on impact against the hardened surface of an armor plate, to dig into such surface at a number of points so as to scarify or break up and thus effectually to disintegrate the portion 65 of the hard surface of the plate struck by the cap and thus better to prepare the remainder of the plate behind such surface for being more easily and successfully perforated by the projectile than heretofore.

The roughened, serrated, ribbed or irregular surface of the cap can be variously formed. Thus, it may consist of a comparatively large number of small projections or teeth of pyramidal, conical or conoidal shape, 70 or in the form of knife blades or edges and be arranged in various ways. Or it may consist of a comparatively small number of such projections or teeth, for instance of a few short projections or teeth of pyramidal 75 form. The projections, teeth, ribs or rib may be of pointed shape, or of truncated shape, or some may be pointed and others truncated.

In the accompanying illustrative drawings, Fig. 1 shows in central longitudinal section, part of a cap fitted to an armor piercing projectile and having a roughened surface according to the invention, the cap and projectile being shown provided with 80 a hollow point or air deflector. Fig. 2 is a developed view showing part of the roughened surface of the cap shown in Fig. 1. Figs. 3, 5, 7 and 10 are similar views to Fig. 1 and Figs. 4, 6, 8, and 9, are similar views 85 to Fig. 2, showing modified constructions.

Referring to Figs. 1 and 2, *a* is a cap fitted to a projectile *b* and provided with a hollow point or air deflector *c*, part only of which is shown. The front end portion of the cap 100

is provided with a roughened surface composed, in this example, of a comparatively large number of projections d of pyramidal shape arranged to form a series of parallel 5 grooves and projections.

In Figs. 3 and 4, the projections d^1 are of conical shape and in Figs. 5 and 6 the projections d^2 are of conoidal shape.

In Figs. 7 and 8, the forward end of the 10 cap a is provided with a comparatively small number of projections d^3 , shown as of pyramidal form, arranged in circular rows and staggered with relation to one another.

The projections may be pointed, as shown 15 at d , d^1 , d^2 , d^5 in Figs. 1 to 8 inclusive or they may be of truncated shape, as shown at d^* in Figs. 3 and 5, or both forms may be used on the same cap.

Where segmental ribs are used, they may 20 be staggered as shown at d^8 in Fig. 9. Also, the free ends of such ribs may be sharp as shown at d^{10} in Fig. 9, or truncated, as shown at d^* in Fig. 10, so as to provide a larger number of cutting edges.

25 The roughened surfaces may be produced by knurling, moulding, stamping, forging, cutting or otherwise, according to their nature.

Such a cap is or may advantageously be hardened, or hardened and tempered, in any suitable or known way, so as to impart desired qualities thereto and so as to produce a hardened, and, it may be, tempered, roughened, serrated or irregular front end 35 surface thereon.

As will be readily understood, a cap constructed as described and shown will, upon 40 striking an armor plate, act to disintegrate or break up the hard surface of the plate and facilitate the perforation of the plate by the projectile to which the cap is fixed.

The invention can be applied to caps of 45 various shapes such as those hereinbefore indicated, or other shapes, and over any desired proportion of the front end portion thereof.

What we claim is:—

1. For an armor piercing projectile having a hardened and tempered ogival shaped 50 pointed head, a cap, the rear end portion of which is recessed and adapted to fit over and be secured to the ogival shaped head of the projectile and the front end portion of which is provided with a plurality of 55 independent hardened projections adapted to dig into and scarify the surface of a hard faced armor plate and each extending only a comparatively short distance around the circumference of the cap.

60 2. For an armor piercing projectile having a hardened and tempered ogival shaped pointed head, a cap, of substantially ogival shape externally, the rear end portion of the cap being recessed and adapted to fit over

and be secured to the ogival shaped head 65 of the projectile and the front end portion of the cap being provided with a plurality of forwardly extending hardened projecting portions arranged at varying distances from the extreme front end of the cap and each 70 extending only a comparatively short distance around the circumference of the cap.

3. For an armor piercing projectile having a hardened and tempered ogival shaped pointed head, a cap the rear end portion of which is recessed and adapted to fit over and be secured to the ogival shaped head 75 of the projectile and the front end portion of which is provided with a plurality of forwardly projecting hardened portions located 80 at different distances from the extreme front end of the cap and inclined at different angles to the longitudinal axis of the cap.

4. For an armor piercing projectile having a hardened and tempered ogival shaped pointed head, a cap the rear end portion of which is recessed and adapted to fit over and be secured to the ogival shaped head of the projectile and the front end portion of which is provided with a plurality of 85 forwardly projecting hardened portions located at varying distances from the extreme front end of the cap, each projection being of gradually decreasing cross-sectional area toward its free end and having a base that extends only a comparatively short distance around the circumference of the cap.

5. For an armor piercing projectile having a hardened and tempered cap the rear end of which is recessed and adapted to fit 100 over and be secured to the pointed head of the projectile and the front end portion of which is of convex shape and provided with a plurality of hardened projections of tapering shape located at varying distances 105 from the extreme front end of the cap, each projection having a base that extends only a comparatively short distance around the circumference of the cap and a sharp forward end.

6. For an armor piercing projectile, a cap the front end portion of which is provided with a plurality of projections arranged in parallel rows.

7. For an armor piercing projectile, a cap 115 the front end portion of which is provided with a plurality of projections each of pointed shape and extending only partly around the circumference of the cap.

8. For an armor piercing projectile, a cap 120 the front end portion of which is provided with a number of projections arranged in staggered relationship.

9. For an armor piercing projectile, a cap the front end portion of which is provided with a number of projections arranged in staggered relationship and of pointed shape.

10. For an armor piercing projectile, a cap the front end portion of which is provided with a plurality of projections of pyramidal shape.
11. For an armor piercing projectile, a cap the front end portion of which is provided with a large number of closely pitched projections.
12. For an armor piercing projectile, a cap the front end portion of which is pro-
- vided with a large number of closely pitched projections of pointed shape.
13. For an armor piercing projectile, a cap the front end portion of which is provided with a large number of closely pitched 15 projections of pyramidal shape.

Signed at London, England, this eighteenth day of November, 1918.

ROBERT ABBOTT HADFIELD.

ALEXANDER GEORGE MCKENZIE JACK.
